Inventor:
Clark R. Phiffer,
by *Merle D. Hunt*
His Attorney.

UNITED STATES PATENT OFFICE.

CLARK R. PHIFFER, OF SCHEENECTADY, NEW YORK, ASSIGNOR TO GENERAL ELECTRIC COMPANY, A CORPORATION OF NEW YORK.

ADAPTER FOR VACUUM TUBES.

Application filed July 23, 1926. Serial No. 124,503.

My invention relates to improvements in adapters employed in connection with standard base members.

In the co-pending application of James H. Mosher, Serial No. 113,321, filed June 2, 1926, there is disclosed a standard base member within which an adapter socket is so mounted that vibrations cannot be transmitted through the base to the discharge device mounted in the socket. The supporting means disclosed in the above identified application consists of a plurality of thin wire, coil springs which are compressed and expanded when a discharge device is inserted in or withdrawn from the socket. In order to prevent damage or any undue distortion to the springs under such circumstances, I have provided means independent of the spring supports for limiting the longitudinal or rotational movement of the socket member without in any way interfering with the action of the springs in preventing the transmission of vibrations to the discharge device.

The novel features which I believe to be characteristic of my invention are set forth with particularity in the appended claims. My invention itself, however, will best be understood from reference to the following specification taken in connection with the accompanying drawing in which Fig. 1 is a view partly in elevation and partly in cross-section of a device embodying the features of my invention; Fig. 2 is an exploded view of the device shown in Fig. 1, while Fig. 3 is a plan view of a standard base member with a socket for a discharge device mounted therein.

Referring to the drawing, I have indicated at 1 an insulating cup-shaped member or base of standard form which is provided with four hollow terminals 2. An insulating socket member or adapter 3, which comprises upper and lower sections 4 and 5 respectively, joined together by a central rivet 6, is mounted in the base 1 and spaced therefrom. A plurality of coil springs 7 are inserted in base 1 and support the socket member 3 therein. Each spring is electrically connected at one end to one of the hollow electrodes 2 and at the other end to a metallic member 8 mounted in socket 3. A portion of each member 8 is bent outwardly, as indicated at 9, and soldered to the upper portion of spring 7.

Base 1 is provided on its periphery with a

plurality of relatively large openings 10 and a projecting portion 11, as indicated in Figs. 2 and 3. In the assembly of the socket and base, the lower ends of the springs 7 are first soldered to the hollow terminals 2. Pins 12 are then inserted through the center of the relatively large openings 10 and driven into the lower portion 5 of the socket member 3. The pins 12 do not normally engage the sides of the openings but when a tube or discharge device 13 is inserted in socket member 3 the latter member is depressed until pins 12 engage the lower portions of openings 10, after which the tube may be firmly inserted into the socket. Likewise, when the tube is removed, pins 12 engage the upper portion of openings 10 and permit removal of the tube without causing any undue distortion of the spring supports.

A cap or cover member 14 provided with depending fingers 15 and a felt lining 16 is slidably mounted on the socket member 1, the depending fingers being spaced apart to accommodate the pins 12 and the projecting portion 11.

What I claim as new and desire to secure by Letters Patent of the United States, is:

1. In combination, a cup-shaped member provided with a plurality of projecting terminals, a socket adapted to support an electric discharge device, said socket being spaced from and flexibly supported in said cup-shaped member and provided with a plurality of openings, contacts mounted in said openings and electrically connected to said terminals, and means independent of said flexible support for limiting the longitudinal movement of the socket member when a discharge device is inserted in or withdrawn from the socket.

2. In combination, a cup-shaped member provided with a plurality of projecting terminals, a socket adapted to support an electric discharge device, flexible means for supporting the socket in the cup-shaped member and in spaced relation thereto and means on said socket adapted to engage the cup-shaped member and thereby limit the longitudinal movement of said socket member when a discharge device is inserted in or withdrawn from the socket.

3. In combination, a cup-shaped member having a plurality of projecting terminals

and a plurality of openings in the periphery thereof, a socket member adapted to support an electric discharge device, said socket being resiliently mounted in the cup-shaped member and provided with a plurality of openings, contacts mounted in said openings and electrically connected to said terminals, and a plu-

rality of pins mounted on the socket and projecting through the openings in the periphery of said cup-shaped member to limit movement of the socket in said cup-shaped member.

In witness whereof, I have hereunto set my hand this 21st day of July, 1926.

CLARK R. PHIFFER.
